UNITED STATES PATENT OFFICE.

ROBERT C. MATHES, OF NEW YORK, N. Y., ASSIGNOR TO WESTERN ELECTRIC COMPANY, INCORPORATED, OF NEW YORK, N. Y., A CORPORATION OF NEW YORK.

VACUUM-TUBE REPEATER.

Application filed November 4, 1916. Serial No. 129,463.

To all whom it may concern:

Be it known that I, ROBERT C. MATHES, a citizen of the United States, residing at New York, in the county of New York and State of New York, have invented certain new and useful Improvements in Vacuum-Tube Repeaters, of which the following is a full, clear, concise, and exact description.

This invention relates to vacuum tube repeaters, in which a variable source of potential, such as a storage battery, is provided for the plate or output circuit, and has for its object to provide method and means for minimizing the variations in amplifying power due to the inconstancy of the potential of the source.

A further object of the invention is to provide a method and means for preserving the impedance balance in case it is necessary to use a transformer having a ratio not suitable to the normal impedances at opposite sides thereof, and in general to improve the transmission of alternating currents through a vacuum tube repeater or amplifier.

The alternating current in the output circuit of the vacuum tube depends upon the sum of the internal impedance of the tube and the impedance in that portion of the output circuit external to the tube. The change in amplifying power is due to the variation of the internal impedance of the tube with the change in value of the supplied potential.

The invention provides for making the external impedance larger than the internal impedance whereby the percent of variation in the impedance of the output circuit is, as a whole, reduced, and the amplifying power is made more nearly constant. The transfer of energy from a tube to its external circuit is a maximum when the internal and external impedances are equal, and in increasing the external impedance to steady the amplification, the relative amount transferred is reduced. It is necessary to strike a balance between the variation in amplification due to an unsteady source and the amount of amplification.

The desired value of the external impedance may be secured by choosing a proper

ratio of transformation for the transformer coupling the vacuum tube to the external circuit. If the transformer has N_1 primary, and N_2 secondary turns, and if there be an impedance Z_2 in the secondary circuit, the impedance of this system as a whole is equivalent to an impedance z_1 in the primary circuit of value $z_1 = \left(\frac{N_1}{N_2}\right)^2 Z_2$. This impedance z_1 is known as the equivalent primary impedance, and constitutes all or a part of the external impedance in the output circuit of the tube. By assigning the proper values to N_1 and to N_2 , the equivalent primary impedance may be given any desired value for any specific value of the external impedance Z_2 .

In case the ratio $\left(\frac{N_1}{N_2}\right)^2$ is increased to increase the equivalent primary impedance, then the impedance of the repeater set, which depends upon the reciprocal of this ratio or $\left(\frac{N_2}{N_1}\right)^2$, is correspondingly reduced.

It is another object of the invention to offset the reduction in the impedance of the repeater set consequent upon an increase in the equivalent primary impedance due to a change in the ratio of transformation. This is accomplished by inserting a resistance in circuit with the transformer. By using a proper amount of the resistance inserted in circuit with the transformer, the impedance of the repeater set may be restored to its former value or it may be given any other desired value. If, for example, as often is the case in practice, it is desirable to match the impedance of the repeater set with the impedance of the line, such a resistance is inserted that the resultant impedance of the primary circuit of the transformer when multiplied by the transformer ratio is substantially equal to the impedance of the secondary circuit. By transformer ratio is meant the square of the ratio of turns in the transformer windings.

This will be further considered in connection with the drawings, in which:

Figures 1 and 2 disclose repeating sys-

100

tems; and Figure 3 shows a set of curves giving the relation between the miles gain and the percent of normal "B" voltage for various ratios between the external and internal impedances, for the system shown in Figure 2.

Figure 4 shows a modification in which a resistance may be inserted in the secondary circuit of the transformer instead of in the primary circuit as shown in Fig. 2.

In Figure 1, the repeater 1 is a three-element vacuum tube of the audion type in which the grid 10 is maintained at a suitable potential by the battery 11. The "B" battery 2 in the output circuit is a source of inconstant potential, such as a storage battery, which supplies the space current to the tube through the impedance 7. The condenser 8 passes alternating current but prevents direct current from battery 2 from being supplied to transformer 3. The output circuit of the tube 1 comprises the primary winding of transformer 3, the secondary winding of which supplies an impedance Z_2 which conventionally represents the impedance of a line in which the repeater is connected. This repeater is adapted to repeat without distortion, that is, it provides a faithful reproduction of the currents which it handles in contradistinction to operating as a detector or rectifier.

Looking in the direction *a* from line 5 there is encountered the internal impedance R_o of tube 1; in the direction *b* there is the external impedance or the impedance in the output circuit which is external to the tube. The impedance measured at the line 6 in the direction *c* is the impedance at the secondary side of the transformer 3 or is the impedance of the repeater set. The impedance Z_2 is found on looking in the direction *d* from the line 6.

A so-called "standard" set is one in which the impedance as measured in one direction from line 5 equals the impedance as measured in the other direction therefrom; and equal impedances are measured in either direction from line 6. When the transformer is such as to fulfill these conditions, there is the maximum transfer of energy from the vacuum tube into the line.

Consider such a standard set in which the impedances looking in both directions from line 5 are equal, i. e., the internal and external impedances are equal. The equivalent primary impedance of the standard set is $R_s = aZ_2$ where $a = \left(\frac{N_1}{N_2}\right)^2$. In order to make the equivalent primary impedance larger, the ratio of transformation is changed by making either N_1 larger or N_2 smaller, or by making both N_1 larger and N_2 smaller. Suppose that the number of turns

of the transformer windings have been assigned new values N_1' and N_2' respectively, such as to now make the equivalent primary impedance n times that of the former value. The new value R_s' of the equivalent primary

impedance is $R_s' = a^1 Z_2$ where $a^1 = \left(\frac{N_1'}{N_2'}\right)^2$.

Since n is defined as being the ratio of the two values of the equivalent primary impedance $n = \frac{R_s'}{R_s} = \frac{a^1 Z_2}{a Z_2} = \frac{a^1}{a}$. Of course in the standard set $a^1 = a$ and $n = 1$.

In changing the ratio of transformation to increase the equivalent impedance on the primary side of the transformer, the impedance of the repeater set as seen in direction *C* from line 6, Fig. 1, has been correspondingly reduced. If the number of turns of the transformer windings has been changed so that the equivalent impedance as measured at the primary side of the transformer is n times what it formerly was, then the equivalent impedance at the secondary side of the transformer has been reduced from its former or "standard" value in the proportion of $\frac{1}{n}$.

If the impedance as measured on the secondary side of the transformer, or as measured in the direction *c* from the line 6, has been reduced below the value which it should have in order that the system may function properly when the repeater set is connected to the impedance Z_2 , then the impedance in direction *c* from the line 6 may be raised to its proper value by inserting the proper amount of resistance 4 in the primary circuit of transformer 3, as shown in Fig. 2. Assuming that the coil ratio has been changed so that the equivalent primary impedance is n times its former or "standard" value R_o , then the impedance of the set, i. e., the impedance looking in the direction *c* from line 6, is restored to its former value by inserting a resistance of the value $(n-1)R_o$ in the primary circuit. Or a resistance of proper value may be inserted in the secondary circuit of the transformer, as shown in Fig. 4. While the insertion of a resistance introduces some additional impedance, it also serves to further diminish the fluctuations in gain by adding to the impedance external to the vacuum tube. If, after the coil ratio has been changed, it is not desired to assign a particular impedance value to the set, the resistance element may be omitted, as shown in Fig. 1.

Reference is now made to Fig. 3 which shows how the amplification or miles gain varies when a variable source of potential is used in the output circuit of the tube, as shown in Fig. 2. By "miles gain" is meant the length in miles that a telephone line may

be increased by reason of the presence of the amplifier, a given intensity of current being delivered at the end of the line. From Fig. 3 it is seen that when $n=1$, the miles gain varies from 19.5 to 22 for the maximum variation in voltage when a storage battery, subject to charge and discharge, is used in the plate circuit. The absolute values of gain here given are arbitrary and depend upon the particular design of the repeater set. The numerical differences, however, are the same for all values of total gain. If the ratio $\frac{N_1}{N_2}$ is so increased that $n=2$, as shown in Fig. 3, the variation in miles gain or amplification is reduced, but the actual gain is however reduced. By further increasing the value of n , the variation in gain or amplification is correspondingly reduced. The factors of diminished gain and constancy of gain resulting from these changes must be balanced to meet the requirements of any particular case.

The ratio of the external to the internal impedance of the system shown in Fig. 2 is $(2n-1)R_o$

Fig. 3 shows the various values of this ratio for the different values of n for which the curves are plotted. As indicated opposite the three lower curves, when n is given values of 2, 3, and 4, the external impedances have values of three, five, and seven times the internal impedances, respectively.

In making the external impedance large as compared to the internal impedance when a fluctuating source is used, this system also has the advantage present in the system disclosed in the application of Arnold, Serial No. 85,362, filed March 20, 1916, in which a straight line characteristic is secured for the amplifier by making the external impedance comparable to the internal impedance of the amplifier.

What is claimed is:

1. The method of reducing the variations in amplifying power of a repeater with variations in the voltage of a local source of energy associated therewith, which consists in impeding the output current externally of said repeater to a greater extent than said current is impeded internally of said repeater, thereby repeating without distortion.
2. The method of reducing the variations in amplifying power of a repeater with variations in applied direct current voltage, which consists in impeding the current externally of said repeater to a greater extent than said current is impeded internally of said repeater, thereby repeating without distortion.
3. The method of reducing the variations in amplifying power of a vacuum tube re-

peater with variations in applied direct current voltage, which consists in impeding the current externally of said tube to a greater extent than said current is impeded internally of said tube, thereby repeating without distortion.

4. The method wherein is employed a vacuum tube repeater coupled to an external circuit by means of a transformer, which comprises providing for said transformer a ratio of transformation such that the equivalent external impedance in the output circuit of said tube is larger than the internal impedance of said tube.

5. The method wherein is employed a vacuum tube repeater having an output circuit and a transformer in said output circuit, which comprises providing for said transformer a ratio of transformation such that the equivalent external impedance in the output circuit of said tube is larger than the internal impedance of said tube, and in impeding the currents in said output circuit to give said repeater set a desired impedance.

6. The method wherein is employed a vacuum tube repeater coupled to an outgoing line, which comprises impeding the output current externally of said repeater to a greater extent than said current is impeded internally of said repeater, thereby repeating without distortion.

7. The combination of a vacuum tube repeater having an output circuit, a variable output source of potential therefor, and a impedance in the output circuit of said tube, said impedance having a value greater than that of the internal impedance of said tube, whereby said repeater is adapted to repeat without distortion.

8. The combination of a vacuum tube repeater, a source of variable potential for the output circuit thereof, and a translating system supplied with power by said tube, said translating system having an equivalent impedance larger than the internal impedance of said tube, said translating system comprising a transformer and an impedance energized thereby.

9. The combination of a vacuum tube of the audion type, a space current source of variable potential for said tube, a transformer having primary and secondary windings, means for supplying power to said primary winding from said tube, an impedance supplied with power by said secondary winding, the ratio of transformation of said transformer being such as to give the output impedance external to said tube a value larger than that of the internal impedance of said tube, and means for giving the impedance at the secondary side of said transformer a desired value.

10. The combination of a vacuum tube of the audion type, a space current source of

- variable potential for said tube, a transformer having primary and secondary windings, means for supplying current to said primary winding from said tube, an impedance supplied with current by said secondary winding, the ratio of transformation of said transformer being such as to give the output impedance external to said tube a value larger than that of the internal impedance of said tube, and a resistance in circuit with said primary winding. 5
11. In combination, a transformer comprising primary and secondary windings, an impedance element associated with the secondary winding of the transformer, a transmission circuit associated with the primary winding of the transformer, and means associated with the primary circuit whereby the resultant impedance of the primary circuit 10 when multiplied by the transformer ratio is rendered substantially equal to the secondary impedance. 15
12. In combination, a transformer comprising primary and secondary windings, an impedance element associated with the secondary winding of the transformer, a transmission circuit associated with the primary winding of the transformer, and an impedance element between said transmission 20 circuit and transformer, said last mentioned impedance element being so proportioned that the resultant impedance of the primary circuit when multiplied by the transformer ratio is substantially equal to the impedance 25 of the secondary circuit. 30
13. An arrangement to associate circuits of unequal impedance comprising a transformer, and an impedance element in the primary circuit of the transformer so proportioned that the resultant impedance of the primary circuit when multiplied by the transformer ratio is substantially equal to the secondary impedance. 35
14. An arrangement to associate circuits of unequal impedance comprising a transformer, and an impedance element in the primary circuit of the transformer so proportioned with reference to the transformer ratio and the impedance connected across the 40 secondary terminals of the transformer that the resultant impedance of the primary circuit when multiplied by the transformer ratio is substantially equal to the secondary impedance. 45
15. In combination, a transformer comprising primary and secondary windings, circuits associated with each of said windings, and means associated with one of said windings whereby the resultant impedance 50 of one of said circuits is rendered substantially equal to the impedance of the other circuit multiplied by the transformer ratio. 55
16. In combination, a vacuum tube repeater having an output circuit, a second 60
- circuit, a transformer coupling said circuits, and means associated with one of said circuits whereby the impedance of one of said circuits is rendered substantially equal to the impedance of the other of said circuits multiplied by the transformer ratio. 65 70
17. In combination, a vacuum tube repeater having an output circuit, a second circuit, a transformer coupling said circuits, and a resistance serially connected in one of said circuits said resistance being of such 75 a value that the impedance of one of said circuits is rendered substantially equal to the impedance of the other of said circuits multiplied by the transformer ratio. 80
18. The combination of a vacuum tube of the audion type, a space current source of variable potential for said tube, a transformer having primary and secondary windings, means for supplying current to said primary winding from said tube, an impedance supplied with current by said secondary winding, the ratio of transformation of said transformer being such as to give the output impedance external to said tube a value larger than that of the internal impedance 85 of said tube, a resistance in circuit with said primary winding, said resistance being of such a value that the impedance of the primary circuit when multiplied by the transformer ratio is rendered substantially equal 90 to the impedance of the secondary circuit. 95
19. The method of transmitting currents through a transmission system, which comprises transforming said currents at a ratio tending to unbalance the impedance equality 100 of the system adjacent the point of transformation and substantially restoring the impedance balance by impeding the currents at one side of the point of transformation. 105
20. The method of ballasting an electric translating device the internal impedance of which varies with the applied voltage, which comprises making the external impedance of said device large as compared with the normal internal impedance, thereby rendering 110 the effect of said variations negligible. 115
21. A thermionic repeater having cathode, anode and control electrodes, means for supplying current between said cathode and anode, means connected to said cathode and control electrode for impressing thereon alternating currents to be repeated, and an output circuit connected to said cathode and anode, said output circuit comprising a transformer and a work circuit, the ratio of 120 transformation of said transformer being of such a value that said output circuit has an impedance larger than the impedance between cathode and anode. 125
22. A thermionic repeater having cathode, anode and control electrodes, means for supplying current between said cathode and anode, means connected to said cathode and

control electrode for impressing thereon alternating currents to be repeated, and an output circuit connected to said cathode and anode, said output circuit comprising a 5 transformer and a work circuit, the ratio of transformation of said transformer being of such a value that said output circuit has an

impedance of the order of five times the impedance between cathode and anode.

In witness whereof, I hereunto subscribe 10 my name this 1st day of November A. D. 1916.

ROBERT C. MATHES.
